US00D797429S

(12) **United States Design Patent** (10) **Patent No.:** **US D797,429 S**
(45) **Date of Patent:** **** Sep. 19, 2017**

(54) **SHOE INSOLE**

(71) Applicant: **Spenco Medical Corporation**, Waco, TX (US)

(72) Inventors: **David B. Granger**, Lorena, TX (US); **Jacob Martinez**, Temple, TX (US)

(73) Assignee: **Implus Footcare, LLC**, Durham, NC (US)

(**) Term: **15 Years**

(21) Appl. No.: **29/533,218**

(22) Filed: **Jul. 15, 2015**

(51) LOC (10) Cl. **02-04**

(52) U.S. Cl. **USPC D2/961**

(58) **Field of Classification Search**

USPC ..... D2/953, 957, 958, 959, 960, 968, 946, D2/947, 951, 955, 956, 961, 976; 36/83, 36/88, 91, 92, 93, 94, 95, 96, 97, 98, 136, 36/25 R, 36 R, 43, 44, 71

CLAIM

The ornamental design for a shoe insole, as shown and described.

DESCRIPTION

FIG. 1 is a perspective view of a first embodiment of a shoe insole showing our new design;
FIG. 2 is a bottom view thereof;

FIG. 3 is a top view thereof;

FIG. 4 is a medial side view thereof;

FIG. 5 is a lateral side view thereof;

FIG. 6 is a front view thereof;

FIG. 7 is a back view thereof;

FIG. 8 is a perspective view of a second embodiment of a shoe insole showing our new design;

FIG. 9 is a bottom view thereof;

FIG. 10 is a top view thereof;

FIG. 11 is a medial side view thereof;

FIG. 12 is a lateral side view thereof;

FIG. 13 is a front view thereof; and,

FIG. 14 is a back view thereof.

1 Claim, 10 Drawing Sheets
